W. F. HELMOND

TYPEWRITING MACHINE

Filed Feb. 5, 1919

William F. Belmond Inventor
by B. C. Stickney Attorney.

UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed February 5, 1919. Serial No. 275,172.

To all whom it may concern:

Be it known that I, WILLIAM F. HELMOND, a citizen of the United States, residing in Hartford, in the county of Hartford and State of Connecticut, have invented certain new and useful Improvements in Typewriting Machines, of which the following is a specification.

This invention relates to means for supporting and guiding the carriages of typewriting machines.

The invention is illustrated in connection with the paper carriage of the well-known Underwood typewriter. This carriage is shown as supported partly by two rear guide-rolls, which run upon a guide rail.

Each roll is supported by means of a ball bearing, which is made detachable, and each roll is connected up to its bearing and to the balls in a manner to form a unit, which can be removed bodily from the machine or attached thereto without disturbing the balls or altering the relationship between the roll and the bearing. The invention also provides improved means for adjusting said bearings to compensate for wear.

Another feature of the invention resides in the provision of a novel front guide for the carriage. I have devised a novel ball-bearing roll, which is of such small diameter that it will fit in a very narrow guiding groove or track, while, however, turning upon ball bearings of ample proportions. This novel front carriage roll may have a diameter of about one-fourth of an inch, so that the guiding groove therefor may have but little height, thus permitting the use of such a low front guide bar for the carriage, that the writing line will be easily visible above the bar. Said front roll, although of such small diameter, may run upon bearing balls of say $\frac{3}{32}$ of an inch diameter and arranged in a raceway of ample dimensions. This raceway may be of

greater diameter than said guide-roll, which is supported by the balls running in said raceway. This small guide-roll may project from the carriage into the grooved guide-way or track, and may constitute the sole support for the front of the carriage, so that the use of the usual large front roll for this purpose may be terminated, and the necessity of forming the guiding groove in exact

parallelism with a front rail may also be avoided.

The front carriage-guiding-roll, although of small diameter to permit the use of a low front guide bar, turns freely upon ball bearings, which are of larger dimensions than said guide-roll. It will be understood that the use of the balls permits the supporting of the carriage by means of a roll that projects forwardly from the ball-bearing wheel, since no cramping effect results to retard the movement of the carriage, inasmuch as the balls enable both the wheel and the roll thereon to run smoothly, notwithstanding that the point of support of the carriage is well in front of the vertical plane in which the supporting balls run. Moreover, the roll, with its ball bearings, may be manufactured as a unit and so assembled or disassembled.

Other features and advantages will hereinafter appear.

In the accompanying drawings, Figure 1 is a sectional side elevation of the paper carriage of an Underwood typewriter, provided with front and rear rolls embodying the present improvements.

Figure 2 is an enlarged sectional detail of the front carriage roll.

Figure 3 is a detail of the rear carriage roll unit, with the parts disassembled.

Figure 3^a is a diagram to illustrate the finished condition of a thimble or coupling for the ball cones.

Figure 4 is a part-sectional perspective view of the carriage, illustrating the arrangement of rolls thereon.

The paper carriage comprises rear and front bars 10, 11, and side or end bars 12, 13, forming one casting; and is guided upon a rear cylindrical rail 14 by means of guide-rolls 15. The front of the carriage is supported upon a rail or track 16, which will presently be described.

Each of the rear rolls is peripherally grooved at 17 to fit upon and cling to the rear guide rail, and each may have also a peripheral clearance groove 18, to avoid frictional contact with the top of the rail. In the rear of the roll is formed a ball cup 19, and in the front of the roll is provided a similar ball cup 20. To co-operate with these cups to form raceways for front and rear sets of balls 21, are two cones 22, 23,

which are fixed to the carriage, said cones facing each other to confine the balls in the raceways.

Extending through bores 24, formed in the cones, is a tube or bushing 25, which is forced into said bores 24, and has on its forward end a head 26, and at its rear end is spun over at 27 to form a head pressing against the rear face of the rear cone 22 to 5 adjust or draw the two cones together permanently, and take up all play in the ball bearings, a space being left at 27^a between said cones, to permit them to approach each other while said head is being spun over, 10 and also to permit any further play to be 15 taken up in the ball bearings that may accrue from wear.

Said bushing 25 fits upon a supporting stud 28, which, at its forward end 29, is 20 threaded into a hole 30 in the rear part of the carriage. Said stud has a flange 31 to fit against a vertical finished bearing or surface 32 on the rear carriage bar 10, whereby accuracy of positioning of the roll 15 is secured; and said flange 31 may have a square or octagon form, for convenience in using 25 a wrench to screw the stud into place on the carriage.

Into the rear end of the stud is tapped 30 a confining screw 33, whose head may bear against the outer end 27 of said bushing 25, and hold the bushing and cones rigidly against the stud flange 31. This enables 35 said cones 22, 23 to afford a rigid and accurately-positioned bearing or support for the guide-roll 15, so that the carriage is rigidly guided. There is no play of the roll in either axial or radial direction. The 40 unit, consisting of the roll, the cones, balls, and the bushing, is capable of accurate and cheap manufacture, and may be readily assembled and disassembled by unskilled hands.

It will therefore be seen that each roll 15 45 may run upon two series of balls 21, the roll having the front and rear cups 20 and 19 to co-operate with the central cones 23 and 22 to form the two raceways for the two series of balls; these cones or complementary bearings being stationary upon the carriage, and forming the aforesaid bearing for the roll. To enable this bearing and the roll, together with the balls, to be assembled and disassembled as a unit, the cones 50 are coupled together, so that all the balls are permanently confined between said cones and the cones in the roll itself. These internal cones are centrally perforated and, as above explained, are mounted upon the 55 stud or shaft 28 projecting from the frame of the typewriter carriage; and they are rigidly fastened to the carriage to form a stationary bearing over which the balls travel as the carriage runs. The unit there- 60 fore comprises the roll, the balls, and the 65

stationary cones. In other words, the stationary bearing is connected with the roll and the balls to form a unit; said stationary bearing movable with the roll when taken from the machine, but being immovable 70 upon the carriage when in use.

As heretofore explained, in order to secure said cones together, there is employed the interior tubular bushing 25, whose ends have the external flanges or heads 26 and 27 to 75 confine the cones against separation. This bushing is originally provided with the head 26, and after the balls are inserted and confined in the raceways, the bushing is inserted in the bores in the cones, and another 80 head 27 is spun or formed upon the opposite end of the bushing, thereby taking up all play between the cones and the balls, and also giving the parts the character of 85 a permanent unit.

The space 27^a is left between these bearing cones, so as to permit them to be pressed towards each other at the operation of spinning the head upon the coupling or bushing. This space between the cones also permits the subsequent taking up of wear by spinning the head more tightly upon the coupling or bushing, thus bringing the cones more closely together and taking up any play that may have developed. This produces a durable roller bearing, which can be readily assembled and disassembled, and can hold the carriage tightly, and at the same time permit the carriage to have the 90 required sensitiveness.

Said connecting bushing 25 may fit directly upon the bearing stud 28 on the carriage. Said stud may, as heretofore explained, be threaded into the hole 30 provided in the carriage, and may have formed 105 thereon the head 31 for turning the same by the use of a wrench, said head being adapted to fit against the vertical finished bearing or face 32 upon the carriage, whereby accuracy of location of the roll may be secured. 110 The tip of the stud may be drilled and tapped to receive the screw 33 which confines the roll upon the stud. By taking out this confining screw, the roll may be withdrawn, and subsequently it may be replaced, 115 all in a simple manner, without use of special tools or need of skill.

At the front of the carriage, a stud in the form of a screw 34, having a shank 35 and a head 36, is threaded into a hole 37 made 120 in the front carriage bar 11, and a bearing in the form of a pair of cones 38 is fixed to the carriage by means of this screw. A single series of guiding balls 39 runs in a raceway formed partly by said cones and partly by a V-groove 40 formed internally 125 in a relatively large portion 41 of a carriage roller. Projecting forwardly from the center of said portion 41 is an integral portion 42 of relatively small diameter upon 130

which the front of the carriage is supported and guided. The small portion 42 fits and runs in a groove 43 formed in bar 16, which is in the nature of a flange or rim projecting 5 upwardly from the usual plate 45 provided upon the front of the framework of an Underwood typewriting machine, and bearing the usual front scale 46 of the typewriter, to co-operate with index 47. It will be seen 10 that, owing to the small diameter of the guiding roll 42 and consequent little height of the guiding groove or track 43, its flange or rim 16 may be made comparatively low, and in fact may be made to stand no higher 15 than the front bar 11 of the carriage itself, and hence there is no interference with the reading of the typewriting upon the front of the platen 44. The portion 41 may be covered by a small housing 50 formed upon 20 the front bar of the carriage.

The point of bearing of the guide-roll upon the upper and lower guiding surfaces or tracks in the groove, is so close to the plane in which the bearing balls run, that 25 the tendency to cramp is not excessive; and the effect of such tendency is overcome by the use of the balls themselves, which run freely, even when supporting considerable pressure.

It will thus be seen that in carrying out 30 this feature of the invention in its preferred form, as explained above, I fix upon the front of the carriage the pair of cones 38 for the set of bearing balls 39, which may 35 consist of the single circular row or series. Upon these cones I mount the roller, by means of the large portion 41 which has the interior V-groove, to which said cones are complementary, forming the raceway for the 40 set of balls. From this projects forwardly the portion 42 which has the appearance of a hub, and which may be of such small diameter as to require a guide-groove 43 of but little height. The lower surface of the 45 groove is a carriage-supporting rail, and the upper surface confines the roller against upward displacement. The stud projecting from the front of the carriage supports said cones. This stud, as already explained, may 50 be in the form of a screw passing through the central opening in said guiding roll, and holding the cones rigidly against the vertical finished bearing or surface on the front 55 of the typewriter carriage.

Said guiding-roll may be bored to accommodate the screw head 36, and the latter may bear against the end or flange 51 of a bushing 48, which is spun over at 49 and permanently connects the cones in the manner 60 already explained in connection with the rear carriage rolls.

It will be seen that the roller, the balls 65 and cones 38 may be combined as a unit by means of the bushing 48 and then readily secured in the machine by the use of the

screw stud 35, and may at any time be readily disassembled without separating the balls or other parts from one another, gaining the advantages already explained in connection with said rear rolls. In other 70 words, the cones may be held together by means of the interior bushing 48 headed at both ends in the manner already explained in connection with the rear carriage guiding-rolls; the bushing being originally headed at one end and spun over to form a head at the other end, thus taking up all play of the balls; and the cones may be also separated slightly to permit such play to be taken up, both when the device 75 is manufactured, and also subsequently when the parts have become loose through wear.

Variations may be resorted to within the scope of the invention, and portions of the 80 improvements may be used without others.

Having thus described my invention, I claim:

1. The combination with a typewriter carriage, of a track, a roll to support said carriage and guide it upon said track, said roll having front and rear cups, a pair of cones to co-operate with said cups to form two raceways, bearing balls in the raceways, means coupling said cones together, said 90 coupling means, said cones, said balls and said roll forming a unit, a detachable stud or shaft provided with means to hold said pair of cones rigidly upon the carriage, a finished bearing surface on said carriage, 95 a head on said stud, and means for firmly fastening said stud to said carriage with said head against said finished bearing surface.

2. The combination with a typewriter carriage, of a track, a roll to support said carriage and guide it upon said track, said roll having front and rear cups, a pair of cones to co-operate with said cups to form two raceways, bearing balls in the raceways, means coupling said cones together, said 100 coupling means, said cones, said balls and said roll forming a unit, a detachable stud or shaft provided with means to hold said pair of cones rigidly upon the carriage, 105 said cone-coupling means comprising a tubular bushing fitting tightly in the cones, and having at its ends external flanges to confine the cones against separation, a head 110 on said stud forming a limiting stop for one end of said bushing, and a detachable fastening means forming a limiting stop for the other end of said bushing, said head and fastening means serving as means for accurately positioning the bearing on said 115 stud.

3. The combination with a typewriter carriage, of a track, a roll to support said carriage and guide it upon said track, said roll having front and rear cups, a pair of 120

4

cones to co-operate with said cups to form two raceways, bearing balls in the raceways, means coupling said cones together, said coupling means, said cones, said balls and 5 said roll forming a unit, a detachable stud or shaft provided with means to hold said pair of cones rigidly upon the carriage, said cone-coupling means comprising a tubular bushing fitting tightly in the cones, and having at its ends external flanges to confine the cones against 10 separation, a finished bearing surface on said carriage, a head on said stud, means for firmly fastening said stud to said carriage with said head against said finished bearing surface, said head forming a limiting stop for one end of said bushing, and a detachable fastening means forming a 15 limiting stop for the other end of said bushing, said head and fastening means thus serving as means for accurately positioning said roll with respect to said carriage.

4. The combination with a typewriter carriage, of a track, a roll to support said carriage and guide it upon said track, said 20 roll having front and rear cups, a pair of cones to co-operate with said cups to form two raceways, bearing balls in the raceways, means coupling said cones together, said 25 coupling means, said cones, said balls and said roll forming a unit of mutually interconnected elements, said cone-coupling means comprising a tubular bushing fitting tightly in the cones, and having at its ends 30 external flanges to confine the cones against separation, the play of said balls being taken up by means of said bushing, one of whose flanges is spun over from one end of said bushing to draw 35 the cones permanently against the balls, and a space being left between said cones to permit subsequent taking up of wear by spinning one of said bushing flanges more tightly upon the cones, where- 40 by the bushing may be shortened, a detachable stud or shaft carrying said unit and mounted upon said carriage, and means se- 45 curing said bushing and adjustable to com- 50 pensate for differences in length of the bushing.

5. The combination with a typewriter carriage, of a track, a roll to support said carriage and guide it upon said track, said roll having front and rear cups, a pair of 55 cones to co-operate with said cups to form two raceways, bearing balls in the raceways, means coupling said cones together, said coupling means, said cones, said balls and said roll forming a unit, a detachable 60 stud or shaft provided with means to hold said pair of cones rigidly upon the carriage, said cone-coupling means comprising a tubular bushing fitting tightly in the cones, and having at its ends external 65 flanges to confine the cones against separa-

tion, the play of said balls being taken up by means of said bushing, one of whose heads is spun over to draw the cones permanently towards each other, and a space being left between said cones to permit subsequent taking up of wear by spinning one of said bushing heads more tightly upon the cones, said stud threaded into a hole provided in the carriage and having formed thereon a head, said carriage having a finished bearing face against which said head fits, said stud projecting from said head, and a screw threaded upon the projecting end of said stud to clamp the cones against said head.

6. The combination with a typewriter carriage, of a bearing roller therefor comprising two circular portions of different diameters, a guideway for the carriage in the form of a confining groove in which the 85 smaller portion of the roller fits, a stud upon said carriage, cones upon said stud, the larger portion of said roller having an interior V-groove to co-operate with said cones to form a raceway, and rolls running in said 90 raceway.

7. In a front-strike typewriting machine, the combination with a platen carriage having a frame comprising a front bar, of a front carriage track, a guiding groove ex- 95 tending along said front bar in the rear face thereof, a guiding roller comprising two circular portions whereof one projects forwardly from said carriage to fit in said groove and to be confined thereby against 100 upward displacement, the other of said portions being of greater diameter than the distance between the walls of said groove, balls upon which said other portion turns, and means upon said carriage to carry said 105 balls.

8. The combination with a typewriter carriage, of a pair of cones fixed thereon, a set of balls running upon said cones, a carriage roller comprising a large circular portion 110 having an interior groove to co-operate with said cones to form a raceway for said balls, and also comprising a relatively small circular portion projecting from said large portion, and a grooved carriage-supporting 115 track or guideway within which said roller fits and whereby it is confined against upward displacement.

9. The combination with a typewriter carriage, of a pair of cones, a set of balls running upon said cones, a carriage roller comprising a large circular portion having an interior groove to co-operate with said cones to form a raceway for the balls, and also comprising a projecting circular portion of 125 relatively small diameter, a grooved carriage-supporting track or guideway within which said projecting portion fits and whereby it is confined against upward displacement, and a stud projecting from said 130

carriage to support said cones, said stud being in the form of a screw passing through said roller, and said carriage having a surface against which said screw holds said cones.

10. The combination with a typewriter carriage, of a pair of cones fixed thereon, a set of balls running upon said cones, a carriage-supporting roller comprising a circular portion of relatively large diameter having an interior groove to co-operate with said cones to form a raceway for said balls, and also comprising a circular projecting portion of relatively small diameter, a

15 grooved track member wherein said projecting portion fits and whereby it is confined against upward displacement, and a bushing having heads by which said cones are coupled together.

20 11. The combination with a typewriter carriage, of a pair of cones fixed thereon, a set of balls running upon said cones, a carriage-supporting roller comprising a circular portion of relatively large diameter having an interior groove to co-operate with

25 said cones to form a raceway for said balls, and also comprising a circular projecting portion of relatively small diameter, a grooved track member wherein said projecting portion fits and whereby it is confined against upward displacement, and a bushing having heads by which said cones are coupled together, one of the heads of said bushing being drawn over to draw the cones 30 permanently towards each other.

12. The combination with a typewriter carriage, of a pair of cones fixed thereon, a set of balls running upon said cones, a carriage-supporting roller comprising a circular portion of relatively large diameter having an interior groove to co-operate with

40 said cones to form a raceway for said balls, and also comprising a circular projecting portion of relatively small diameter, a grooved track member wherein said projecting portion fits and whereby it is confined against upward displacement, and a bushing having heads by which said cones are coupled together, one of the heads of 45 said bushing being drawn over to draw the cones permanently towards each other, and a space being left between the cones to enable wear to be taken up by spinning or forcing one of said bushing heads.

55 13. The combination with a typewriter carriage, of a pair of cones, a set of balls running upon said cones, a carriage roller comprising a large circular portion having an interior groove to co-operate with said 60 cones to form a raceway for the balls, and also comprising a projecting circular portion of relatively small diameter, a grooved carriage-supporting track or guideway within which said projecting portion fits and 65 whereby it is confined against upward dis-

placement, a stud projecting from said carriage to support said cones, said stud being in the form of a screw passing through said roller, and said carriage having a surface against which said screw holds said cones, 70 and a bushing having heads by which said cones are coupled together; said roller, cones and bushing forming a unit which may be detached from and attached to said carriage by means of said screw.

75 14. In a typewriting machine, in combination, a laterally-movable carriage, a supporting member therefor, a roller comprising a circular portion of relatively small diameter projecting from said carriage, and a groove being formed in said supporting member to form a track and guideway in which said small portion of said roller runs and in which said portion fits and whereby it is confined against upward displacement, 80 said roller also comprising a circular portion of relatively large diameter clear of said groove and provided with an anti-friction support upon said carriage.

85 15. The combination with a typewriter carriage, having a finished bearing surface, of a track for guiding said carriage, a guide roll to run upon said track, a stud having means detachably supporting it upon said carriage and comprising an integral head 90 or shoulder to bear against said finished bearing surface between said roll and said carriage, a ball-bearing device to support said roll wholly upon said stud, said ball-bearing device comprising circularly-arranged balls and adjacent cones to confine them, said cones removable from said stud, and means for releasably retaining said ball-bearing device upon said stud while the latter remains fixed to the carriage.

100 16. A typewriter carriage supporting and guiding roller, comprising a pair of cones or bearings, a supporting stud therefor having means whereby it may be detachably secured to the carriage, said carriage-supporting roller comprising a circular portion of relatively large diameter provided with an interior groove to co-operate with said cones to form a raceway, and balls running in said raceway, said roller also comprising a circular projecting portion of relatively small diameter to run upon the carriage-supporting rail.

110 17. A typewriter carriage supporting and guiding roller, comprising a pair of cones or bearings, said carriage-supporting roller comprising a circular portion of relatively large diameter provided with an interior groove to co-operate with said cones to form a raceway, balls running in said raceway, 120 said roller also comprising a circular projecting portion of relatively small diameter to run upon the carriage-supporting rail, and a bushing within said cones, said bushing confining said cones against separation 125 130

and combining the cones, balls and roller into a unit.

18. A typewriter carriage supporting and guiding roller, comprising circular portions of large and small diameter, respectively, said large portion having an interior groove, a bearing device confined within said large portion and having a peripheral depression or construction to co-operate with said 10 groove to form a raceway, and balls in said

raceway, said bearing device comprising means whereby it is combined with said balls and said roller to form a unit, and said small portion projecting from said large portion of said roller to run in a grooved 15 carriage-supporting track.
